(57) **CLAIM**

The ornamental design for a food container, as shown and described.

DESCRIPTION

FIG. 1 is a top perspective view of a food container.

FIG. 2 is a bottom perspective view thereof.

FIG. 3 is a top perspective view thereof, attached to a beverage container and a peel off lid, shown reduced in scale.

FIG. 4 is a bottom perspective view thereof, attached to a beverage container and a peel off lid, shown reduced in scale.

FIG. 5 is a top perspective view thereof, detached from a beverage container and a peel off lid, shown reduced in scale.

FIG. 6 is a bottom perspective view thereof, detached from a beverage container and a peel off lid, shown reduced in scale.

FIG. 7 is a top view of FIG. 1.

FIG. 8 is a bottom view thereof.

FIG. 9 is a front view thereof (rear view is mirror image); and,

FIG. 10 is a left side view thereof (right side is mirror image).

The broken lines represent environment that forms no part of the claim.
